COMBINED TOILET PAPER HOLDER, TOWEL RACK, AND HOOK

Sigmund J. Gralewicz, Milwaukee, Wis.

Application August 15, 1956, Serial No. 42,614

Term of patent 7 years

(Cl. D4—3)

The figure is a perspective view of a combined toilet paper holder, towel rack, and hook showing my new design.

The characteristic features of the design are shown in full lines.

I claim:

The ornamental design for a combined toilet paper holder, towel rack, and hook, as shown and described.
